UNITED STATES PATENT OFFICE

NILS MELLGREN, OF GOTTERBORG, SWEDEN

MANUFACTURE OF HEAT EVOLVING CARTRIDGES

Application filed December 3, 1930. Serial No. 499,821.

In the U. S. Patents Nos. 1,417,075 and 1,498,323 there are described heating cartridges composed of an alumino heat evolving mixture enclosed within a casing which according to the last mentioned patent preferably consists in sheet aluminium. According to the first mentioned patent the mixture is compressed leaving a cavity therein to receive an igniting mixture.

10 The object of this invention is a method in the manufacture of heating cartridges of the class mentioned which will improve the igniting properties of said cartridges.

When manufacturing the cartridge the heat evolving mixture will be compressed within its casing by means of a stamp comprising two reciprocating parts, viz. one cylindric central plunger and one annular plunger with a central bore through which the central plunger moves. Of said two plungers the central one at first will be lowered down into the empty cartridge casing, whereby its throw is of such a length, that the plunger stops at some distance above the bottom of the cartridge casing and remains for some moment in this position forming a core for the heat evolving mixture in powder shape which now is poured into the cartridge casing. On account of the core forming central plunger a certain portion of the casing will not be filled up with the powdered mixture, said portion corresponding to the cavity intended for the priming composition. The next operation will be that the annular plunger descends against the mixture in the casing and compresses same sufficiently. Because of the still downwards position of the core forming central plunger that portion of the mixture within the cartridge casing which lies below the central plunger will be withdrawn from the heavy pressure of the annular plunger, thus leaving said portion of mixture in a somewhat softer consistence than is the main body of the same mixture in the casing.

Now the annular plunger will be raised, and as soon as said plunger has released the pressure upon the mixture in the cartridge casing, the central plunger also will be removed leaving the cavity in the cartridge for

the priming composition to be supplied therein.

Experience has shown that the softness of the cartridge mixture below the cavity for the priming composition is of importance for the easy ignition of the cartridge, as also that the wanted degree of softness can be obtained only if the two reciprocating plungers have a special design such as described below with reference to the annexed drawing. In said drawing an embodiment of the main parts of the compressing machine is shown diagrammatically.

Fig. 1 is a sectional elevation view of the machine with a cartridge under operation,

Fig. 2 shows a plan view of a guide wheel,

Fig. 3 is a similar view of another guide wheel, and

Fig. 4 is on an enlarged scale a sectional elevation view of the cartridge when ready to receive the priming mixture.

In the drawing 1 designates the stanchions of the compressing machine, and 2 a shaft carried in bearings 3 on the top of the stanchions and receiving rotation from some power source by means of a belt pulley 4. The shaft 2 is provided with two wheels 5 and 6 stationarily secured to the shaft and provided each with a curved notch 7 and 8 respectively, the notch 7 in the wheel 5 curved in another way than the notch 8 in the wheel 6 as can be seen in Figs. 2 and 3 in which figures the two wheels are seen from those sides which are in front of each other in the machine as per Figure 1, and the wheels disposed in the same mutual relation as in the machine as it concerns the curvatures of their notches.

A table 9 connects the two stanchions 1, as also somewhat above said table a guide 10. On the table 9 there is a mould 11 for the cartridge which is to be manufactured, into which mould the metal casing 12 for said cartridge is supplied.

In the notch 7 of wheel 5 moves the head 13 of a rod 14 the lower part of which forms a sleeve 15 guided within the guide 10, and terminates in an annular plunger head 16 which suits the cavity of the cartridge casing 12. In notch 8 of wheel 6 a similar head

17 of a rod 18 is movable, the thicker lower part 19 of said rod passes through the central bore in the sleeve 16 as also in the annular plunger 16 and thus constitutes a central plunger, surrounded by the annular plunger 16.

When revolving the shaft 2 the notches 7 and 8 will cause the rods 14 and 18 with their plungers 16 and 19 to reciprocate in such mutual strokes that at first plunger 19 descends into the casing 12 on the table 9, and, having reached its downmost position as exemplified in Fig. 1 leaving some distance free above the bottom of cartridge casing 12, the annular plunger 16 descends until its downmost position, shown in the same figure. When continuing its revolving, shaft 2 by means of the notches 7 and 8 in the wheels 5 and 6 respectively raises at first the annular plunger 16 off from the casing 12, and somewhat later the central plunger 19 also becomes lifted. These mutual movements of the two plungers are performed by the mutual shapes and dispositions of the notches 7 and 8 in the wheels 5 and 6.

The powdered mixture for the cartridge is poured into the casing 12 as described above, and when the said compressing action has been completed the cartridge is removed from the table 9, and has the appearance shown on an enlarged scale in Fig. 4. From this figure it is visible that the central cavity 20 left by the withdrawn central plunger 19 is of a conical appearance. That depends on the fact that the operative end 22 of the central plunger 19 is bevelled. The reason for said bevelled shape of the plunger is to get that portion 23 of the mixture which is positioned below the cavity 20 less compressed than the main body 24 of said mixture, for the purpose to have the cartridge more easy to ignite when firing the priming composition which is to be supplied into the cavity 20 before the cartridge is ready for use.

Should the central plunger 19 be cylindric the pressure upon the main body of the mixture 24 from the annular plunger 16 will cause substantially the same pressure to be transmitted to the central portion 23 also, and the intended object would not be attained. But as the central plunger end 22 is bevelled the pressure from the annular plunger 16 is removed off from the central portion 23, as is demonstrated by the dot-and-dash lines 25 in Fig. 4 which indicate the boundaries of a cylindrical portion of the mixture 24 which will be somewhat re-

leased from the pressure from plunger 16, whilst the crosswise scattered portion below the cavity 20 indicates the soft compressed central portion 23.

When the priming composition has been supplied into cavity 20 a lid 26 shown by dot-and-dash lines in Fig. 4 is placed above the casing 12, and the cartridge is ready for delivery.

What I claim is:

1. A method of manufacturing heat evolving cartridges having a central cavity for a priming composition, consisting in subjecting the portion of the active mixture of the cartridge underlying the central cavity to less pressure than the main body of said active mixture surrounding said central cavity whereby the portion of said mixture below said cavity is softer than the main body thereof.

2. An apparatus for the manufacture of heat evolving cartridges having a central cavity for a priming composition, comprising two reciprocable plungers, one of said plungers having a substantially conical end surface adapted to form the central cavity for the priming composition in the active mixture of a cartridge, the other plunger having a central bore slidably receiving the first mentioned plunger and surrounding the latter at its working end to compress the main body of the active mixture around said cavity, and means for operating said plungers whereby the first mentioned plunger following the formation of the central cavity in the active material acts to prevent further compression of the active material underlying said cavity during the compression of the main body of the active material by the second mentioned plunger.

3. A method of manufacturing heat evolving cartridges having metal casings by means of movable plungers, consisting in advancing one plunger into the metal casing to a point a distance above the bottom of said casing, introducing the powdered active mixture into said casing, advancing the other plunger to compress the active mixture surrounding the first mentioned plunger whereby the portion of the active mixture underlying the cavity formed by the first mentioned plunger remains soft as compared with the main body of the mixture surrounding said cavity.

In testimony whereof I have affixed my signature.

NILS MELLGREN.
